UNITED STATES PATENT OFFICE.

BENNET BRUFLAT, OF BLUE MOUNDS, WISCONSIN.

CARRIER-TRACK.

1,164,779.

Specification of Letters Patent. Patented Dec. 21, 1915.

Application filed July 10, 1915. Serial No. 39,095.

To all whom it may concern:

Be it known that I, BENNET BRUFLAT, a citizen of the United States, residing at Blue Mounds, in the county of Dane and 5 State of Wisconsin, have invented new and useful Improvements in Carrier-Tracks, of which the following is a specification.

This invention comprehends the provision of a carrier track adapted to be arranged 10 on the outside of a barn to form a continuation of a track positioned within the barn, and over which the carrier travels for moving manure or other material from the barn when desired.

15 The object of the present invention resides in the provision of a track for this purpose which is supported for horizontal movement to permit the carrier when moved on the track exteriorly of the building to 20 travel to different discharge positions, with means for manipulating the device as well as locking the track in any of its adjusted positions.

25 The nature and advantages of the invention will be better understood from the following description, wherein the specific construction and arrangement of parts are more fully set forth.

30 In the drawings forming part of this application like numerals of reference indicate similar parts in the several views and wherein:—

35 Figure 1 is a side elevation. Fig. 2 is a top plan view. Fig. 3 is a longitudinal sectional view. Fig. 4 is an enlarged detail view of the bracket with the supporting member and track associated therewith. Fig. 5 is an enlarged transverse detail section.

40 Referring more particularly to the drawings A indicates the wall of a barn and B the door opening therein, above which and to the wall A is adapted to be mounted the device forming the subject matter of my invention, including among other features a 45 movable track 5 adapted to be supported in alinement with the fixed track 6 arranged within the barn when in normal position forming a continuation of the latter, whereby the carrier is permitted to travel from 50 within the barn upon the track 5 for the purpose of removing manure or other material from the barn, and discharging the same in a wagon or other suitable receptacle.

55 Secured to the wall A as shown is an arcuate shaped bracket 10 having elongated

attaching plates 11 at the opposite ends thereof for the purpose of securing the bracket in position. Connecting the attaching plates 11 is a cross plate 12 having 60 formed thereon at a point approximately midway of its length spaced apertured lugs 13 together with the cross plate 12 constituting a hinge member. Pivotaly mounted between the lugs 13 by means of the bolt 65 14 is a supporting rod or member 15 projecting outwardly from the bracket and having secured thereto at spaced intervals one end of a plurality of supporting rods or cables 16, which latter extend upwardly at 70 an angle to a point above the hinge member and connected at a common point in any suitable manner to the wall A, to permit the supporting member to swing in a horizontal plane. As shown the supporting 75 member is disposed above the arcuate shaped bracket 10 and carries at the under side thereof a roller 17 adapted to travel along the upper edge of the arcuate shaped bracket 10 to reduce the friction between the 80 parts as will be readily understood. Fixed to the supporting member 14 approximately at the transverse center thereof is a cross arm 18 which projects an appreciable distance beyond the opposite sides of the member 14 and terminally connected to the intermediate portion of the stay rods 19, which latter are terminally connected to the supporting member 14 adjacent the opposite ends thereof for the purpose of supporting 85 or bracing said member laterally.

90 Suspended from the supporting member 14 by means of the suspension rods 20 is the movable track 5 which may be of any suitable formation, but similar in contour as 95 the fixed track 6 arranged within the barn, so as to form a continuation of the track 6 when the parts are positioned in the manner shown in Fig. 1. The track 5 is disposed in spaced parallel relation to the supporting member 14, while the suspension rods 20 are formed to provide the bulged portions 21 to permit the pulleys (not shown) supporting the carrier to move freely over the track without being interfered with by the suspension rods 20.

100 As hereinabove stated, the supporting member 14 together with the track 5 are mounted to swing in a horizontal plane, so that the carrier when moved from within the barn upon the track 5, is permitted to travel to 105 different discharge position, and with a view

of manipulating the track 5 and locking the same in any of its adjusted positions, I employ a block 22 secured to the under side of the supporting member 14, and through 5 which block is slidably mounted a spring pressed locking bolt 23 for interchangeable engagement with the openings 24 in the arcuate shaped bracket 10 as clearly shown in the drawings. Secured to the end of the 10 bolt 23 is a flexible operating element, such as a chain 25, the latter being movable over guide pulleys 26 supported upon the member 14 at spaced intervals by means of the brackets 27. The outer end of the chain 15 terminates to provide the branches 28 carrying the hand grips 29, which are suspended from the supporting member 14 a suitable distance in convenient reach of the operator.

20 Now when it is desired to swing the track 5 together with the carrier mounted thereon, to any position, for the purpose of discharging the manure or other material contained in the carrier at any desired point, a pull on 25 the chain 25 by means of the hand grips 29 retracts the bolt 23 against the tension of the spring 30, out of engagement with the bracket 10, subsequent to which a further pull in a lateral direction upon the chain 30 will swing the track in the desired direction. When the hand grip 29 is released, the spring 30 operates to automatically return the bolt 23 into operative association 35 with the openings 24 into the bracket 10 thereby holding the track immovable in adjusted position.

It is believed that from the foregoing description the nature and advantages of the invention will be thoroughly understood 40 without requiring a more extended explanation and therefore the same has been omitted. However I desire to have it understood that I do not limit myself to the precise construction and arrangement herein 45 illustrated and described, and that various changes may be resorted to when desired as fall within the scope of the appended claims.

What is claimed is:—

1. A carrier track comprising a hinge 50 member, a supporting member associated therewith for horizontal swinging movement and extending outwardly from said hinge member, supporting means extending upwardly from said supporting member to 55 a point above said hinge member, stay rods bracing said supporting member laterally, a

track suspended from said supporting member and disposed in spaced parallel relation thereto for adjustment therewith, and means for locking said track and member in any 60 adjusted position.

2. A carrier track comprising a bracket including a hinge member, a supporting member pivotally connected with said hinge member and projecting outwardly therefrom for horizontal adjustment, supporting means extending upwardly from said supporting member to a point above said hinge member, stay rods bracing said supporting member laterally, a track suspended 65 from said supporting member in spaced relation thereto, a lock bolt carried by said supporting member for engagement with said bracket for holding said track and member in adjusted position, and means for 70 manipulating said bolt.

3. A carrier track comprising an arcuate shaped bracket, a hinge member connecting the terminals of said bracket, a supporting member pivotally connected with said hinge 80 member and projecting outwardly therefrom above said bracket, a roller carried by said supporting member and movable over said bracket, supporting means for said member, stay rods bracing said member laterally, a track suspended from said supporting member in spaced parallel relation thereto, and means for locking said track and member in adjusted position.

4. A carrier track comprising an aper- 90 tured arcuate shaped bracket, a hinge member carried thereby, a supporting member pivotally associated with said hinge member and projecting outwardly therefrom, a track suspended from the supporting member in 95 spaced parallel relation thereto, supporting means connected with said member, stay rods bracing said member laterally, a spring pressed bolt carried by said member for engagement within said apertures for holding 100 said track and member in adjusted position, guide pulleys carried by said supporting member, and a flexible element connected with said bolt and movable over said pulleys for the purpose described. 105

In testimony whereof I affix my signature in presence of two witnesses.

BENNET BRUFLAT.
